UNITED STATES PATENT OFFICE

130,957

DESIGN FOR AN AUTOMOBILE COOLER

Thomas G. Beckett, Dallas, Tex.

Application March 17, 1941, Serial No. 99,649

Term of patent 3½ years

To all whom it may concern:

Be it known that I, Thomas G. Beckett, a citizen of the United States, residing at Dallas, in the county of Dallas, State of Texas, have invented a new, original, and ornamental Design for an Automobile Cooler, of which the following is a specification, reference being had to the accompanying drawing, forming part thereof.

Figure 1 is a front perspective view of an automobile cooler showing my new design.

Figure 2 is a rear elevational view.

Figure 3 is a side elevational view.

The opposite side of the automobile cooler is substantially similar to that shown in Figure 3.

I claim:

The ornamental design for an automobile cooler, as shown and described.

THOMAS G. BECKETT.
